BLANK FEEDING AND STOPPING
MECHANISM

William Ward Davidson, Evanston, Ill.

Application September 5, 1935, Serial No. 39,278

9 Claims. (Cl. 192—126)

This invention relates to a mechanism for feeding blanks such as cards etc., to a mechanism, such for instance as a photographic mechanism by which the blanks are operated upon one after another and has special reference to a stop mechanism for such a machine.

A particular object of the invention is to cause the substantially instantaneous stopping of the feeding of the blanks if and when two or more blanks are simultaneously fed or when the fed blanks are not completely separated, that is when for some reason the blanks overlap to some extent or if more than the thickness of a single blank is fed to the mechanism.

15 A further object is to provide a mechanism arranged and adapted to be operatively connected with and driven from a primary machine which requires blanks to be fed singly thereto and sufficiently separated that each blank can be operated upon individually.

20 A further object of the invention is to provide a mechanism for the purpose mentioned, which shall be capable of being used either for automatic or manual separation and feed of the blanks and which shall substantially instantaneously stop the mechanism upon the passage through the feed rolls of any superposed or overlapping blanks or sheets.

To the accomplishment of the above noted and other ends, the invention consists in the means hereinafter fully described and particularly pointed out in the appended claims, the accompanying drawings forming part of this specification setting forth in detail one embodiment exemplifying the invention. Such disclosed structure, however, exemplifies but one of various applications of the principal of the invention.

In said drawings:

Figure 1, is a side elevation of a mechanism embodying the invention in one form and shown as arranged in conjunction with a primary machine to which it is desired to successively feed single blanks;

Figure 2, is a fragmentary top plan view of the feed mechanism and associated primary machine.

Figure 3A is a fragmentary, vertical longitudinal section on the line 3—3 of Fig. 2, the parts of the mechanism being shown in normal operating position;

Fig. 3B is a section similar to Fig. 3A but showing parts of the mechanism as moved by the inadvertent simultaneous feeding of more than one blank and effecting the stopping of the mechanism;

Figure 4, is a fragmentary, vertical, transverse section on the line 4—4 of Fig. 2;

Figure 5 is a detail horizontal section on the line 5—5 of Fig. 4; and

Figure 6, is a side elevation, particularly portraying the means for driving the blank separator.

In Fig. 1 of the drawings, a blank feeding mechanism designated generally by the letter A is shown as associated with and mounted on or in connection with a primary machine designated generally by the letter B.

As the primary machine may illustrate any machine which is adapted to operate upon or in connection with blanks, such as cards, which must be fed thereto one at a time, it is not thought to be necessary to describe the primary machine except insofar as it may have parts which co-operate with the feeder A.

As shown in the drawings, the primary machine has a drum 10 which is rotated by means of an electric motor 11 through the medium of a speed reducing mechanism including a belt 12 trained around a relatively large pulley 13 mounted on a shaft 14 and driven by the motor 11 and a second belt 15 trained around a small pulley 16 in the shaft 14 and a larger pulley 17 mounted in connection with the drum 10.

The drum 10 is carried on a shaft 18 which is mounted in suitable bearings on the frame of the primary machine.

The feeder A is driven through the medium of the drum 10 of the primary machine and this present invention relates particularly to relatively simple means for stopping the feeder, while the drum 10 of the primary machine continues to rotate, upon the inadvertent simultaneous feeding of more than one blank or if the fed article is thicker than the thickness of a single blank as arranged for.

The primary machine B has a rigid frame including vertically arranged side members 19 provided with horizontal rearwardly projecting bracket-like parts 20 and suitable cross members including a flat-plate-like cross bar 21 which is secured at its ends to the parts 20.

This bar 21 is arranged at the entrance end of the primary machine B and in proximity to the drum 10.

The feeder A is mounted on and secured to the bracket parts 20 and to the cross-bar 21 and is arranged and adapted to feed the blanks to the primary machine and upon or in contact with the drum 10 for operation thereon by the primary machine.

As shown and described, the feeder A is driven by the primary machine for simplicity and for timing the operation of the feeder with the operation of the primary machine, but obviously, 5 the feeder could derive its power from a source separate from the primary machine without changing the principal of operation of the feeder.

As indicated hereinbefore the feeder may be arranged for manual feed of the blanks or may 10 be provided with means for automatically separating the blanks from a stack and advancing them to and through the feeder to the primary machine. But whether the blanks are manually or automatically fed, the stop mechanism operates to stop the feeder upon the inadvertent feeding of superposed blanks or the passage of more than the thickness arranged for.

The mechanism for advancing the blanks to the drum and for stopping the progress of the 20 blanks upon the passage of more than the thickness arranged for will now be described.

The feeder A, see particularly Figs. 3A and 3B, is provided with blank guiding means comprising inclined guide bars 22 arranged longitudinally of 25 the machine and spaced apart transversely of the machine.

These guide bars, as best shown in Fig. 4, are L-shaped, the horizontal flanges 23 thereof forming the support for the fed blanks as indicated at 30 24, Fig. 4, and the vertical flanges 25 forming the guide to direct the blanks in the desired path toward the drum 10. These guide bars are pivotally mounted between their ends as indicated at 35 26 and their delivery ends 27 project over the drum 10 and are weighted to rest upon the drum. The delivery ends of the guides 22 are provided with anti-friction rollers 28 to avoid any friction with the drum 10.

The pivots 26 of the guide bars 22 are carried 40 by brackets 29 which depend from a rigid cross-frame member 30. The brackets 29 are each provided with a notch 31 to receive the bar 30 and with a clamping screw 32 for securing the bracket in place on the bar 32. By this means the guides 45 22 can be readily adjusted transversely of the machine to accommodate blanks of different widths.

The rear end portions 33 of the guide bars 22 extend a sufficient distance, so as to conveniently 50 receive blanks fed thereto either by hand or automatically from a stack 34.

For driving the feeder a drive roller 35 is provided, mounted on a transversely extending shaft 36 and which roller normally contacts with the drum 10 and is rotated thereby. The roller 35 is movable up and down to a slight extent for the purpose of disengaging it from the drum to stop the feeder or to contact it with the drum to drive the feeder as will now be explained.

60 The roller 35 is secured to rotate with its shaft 36 and the shaft is mounted in bearings on a tilting frame comprising side bars 37 which are secured at their rear ends upon a transverse shaft or rod 38 as shown at 39, Fig. 2.

65 The frame of the feeder comprises side parts or plates 40 and 41 which are rigidly mounted on and rise above the side bracket parts 20 of the frame of the primary machine. These side parts 40 and 41 are secured at their lower edges to longitudinally extending bars 42 and 43 respectively and which in turn are supported on and secured to posts 44 and 45 which are secured to and rise from the brackets 20. The side plates 70 40 and 41 are rigidly connected together by the

cross bar 30 which is secured rigidly at its ends to said plates by corner brackets 46, see Fig. 2.

The roller 35 which is driven by the drum 10 is yieldingly pressed against the drum by a tension spring 49, see Figs. 3A and 3B, the upper end 5 of which engages the free end of a rod 50 rigidly mounted on a cross bar 51 by which the parts 37 of the roller carrying frame are rigidly connected. The bar 51 is positioned near the rear end of the frame of the roller 35 and the rod 50 10 projects toward the roller 35. The lower end of the spring 49 is secured to a vertically adjustable member 52 so that the tension of the spring and the consequent pressure of the roller 35 on the drum 10 can be readily adjusted as may be required. The member 52 as shown comprises a vertically extending rod secured at its upper end in a block 53 having a notch 54 in one edge to receive an edge of the cross bar 21 and adapted to be clamped on the bar 21 by a set screw 55. 20 The rod 52 is adjustably mounted in the block 53 by having a screw threaded engagement therewith and is adapted to be secured in adjusted position by a jam nut 56. The lower end of the rod 52 is bent off at a right angle to provide a 25 horizontally projecting part 57 to which the lower end of the spring 49 is secured. The spring 49 is tensioned sufficiently to hold the roller 35 against the drum 10 with sufficient pressure to properly drive the feeder mechanism.

Below the guides 22 and between same there is arranged a corrugated feed roller 58 mounted on a transverse shaft 59 to rotate therewith. The shaft 59 is mounted for rotation in suitable bearings on the side frame parts 40 and 41 of the 35 feeder frame. The shaft 59 is rotated by a pinion 60 secured on the feed roller shaft 59 which engages a toothed gear 61 secured on the friction roll shaft 36. The arrangement of the geared connection between the shafts 36 and 59 and the 40 pivoted frame on which the roller 35 is mounted is such that the roller 35 can be lifted clear of the drum without interference from the gearing.

The feed roller 58 is positioned substantially midway transversely of the feeder and I provide 45 yielding means for pressing the blanks against the feed roller to cause the blanks to be properly propelled. This yielding pressure means comprises a pair of transversely spaced pressure rollers 62 arranged above the feed roller 58 and the blanks 50 are adapted to be yieldingly pressed toward the feed roller. The blanks pass through between the pressure rollers on top and the roller 58 on the bottom. These rollers are commonly known as the pull-out rolls. For mounting the pressure 55 rollers 62, crank-arms 63 are secured on a transverse shaft 48 and the rollers 62 are rotatably mounted on studs 64 secured in the free ends of the crank arms. The crank arms 63 are secured against rotation on the shaft 48 as by a longitudinal key-way 65 in the shaft and suitable splines carried by the cranks so as to permit ready adjustment of the crank arms transversely of the feeder. The shaft 48 is rotatably mounted in suitable bearings on the side frame parts 40 and 41 and at one end the shaft is provided with a radially extending pin 66 engaged by a tension spring 67, the other end of which is secured to a pin 68 rigidly secured to the adjacent side frame part 41. The arrangement is such that the pressure rollers 62 are yieldingly held pressed toward the feed roller 58.

To stop the feeder I arrange means, controlled by the feeding of any blank or article past the feed roller 58 which is thicker than the thickness 70 75

of a single blank, for lifting the roller 35 free of the drum and thus stopping the application of the power to the feeder.

Loosely mounted for rotation on the shaft 36 of the contact roller 35, I arrange a cam plate 69. This plate is in the form of a disk, the major portion of the periphery 70 of which is of less diameter than the roller 35 and consequently does not contact with the drum 10. At a suitable point in the periphery 70 of the cam disk, I provide an inclined cam projection 71. Preferably this projection is below the line of contact of the roller 35 with the drum 10. The cam projection 71 extends radially beyond the periphery of the roller 35 and when the cam disk 70 is rotated slightly to cause the cam projection to contact with the drum 10, the friction between the cam projection 71 and the drum 10 will drag the cam disk still further around and force the roller 35 out of contact with the drum. As soon as this occurs the application of power to the feeder is stopped. Adjacent to the cam projection 71 I arrange an anti-friction roller 72 carried by the cam disk 69 and adapted to contact with the drum 10 just as the cam projection 71 is freed from the drum. This position is best illustrated in Fig. 3B.

The anti-friction roller 72 is mounted for free rotation on a stud 73 secured to the disk 70 and the periphery of the roller extends slightly radially beyond the cam projection 71 so that as soon as the disk is rotated far enough to bring the roller into the position shown in Fig. 3B the cam is entirely free of the drum 10. A stop projection 74 is carried by the disk 70 and is arranged to contact with a fixed frame part 75 to stop the disk 70 just as the anti-friction roller 72 reaches the position shown in Fig. 3B with the roller 35 out of contact with the drum 10.

For automatically rotating the cam disk to effect the stopping of the feeder, as above described, I provide a simple mechanism adapted to be operated by the feeding of more than a single blank and connected with the disk to rotate same, as follows:

Above the corrugated feed roll 58 there is provided a rock lever 76 pivotally mounted between its ends at 77 to swing back and forth in a vertical plane. The lever 76 has a shoe 78 at its lower end opposed to the feed roll 58 and adapted to be spaced above the feed roll to permit the free passage of a single blank and to be engaged by a double blank or by any article which is thicker than a single blank and be swung to the left, see Figs. 3A and 3B, on its pivot 77.

As will be explained the lever 76 is vertically adjustable to accommodate blanks of different thicknesses. The shoe 78 has a portion 79 which is concentric with the pivot 77 and a rear end portion 80 which is bent slightly upwardly or inwardly so as to serve as a guide for the articles being fed to direct them between the shoe 78 and the roller 58. After the lever 76 has been adjusted to provide a space between the shoe and the roller just sufficient to permit a single blank to pass freely, any article which is too thick to pass freely through the provided space, will cause the lower end 81 of the lever 76 to swing to the left as described.

For mounting the pivot 77 of the lever 76 there is provided a block 82 provided with a gap 83 for receiving the frame bar 30 and the block 82 is rigidly secured in position by set screw 82'. A rod 84 is mounted in a vertical hole in said block and the lower end of the rod 84 extends down below the bottom of the block 82 and carries a rigid

cross bar 85. The pivot 77 of the lever 76 is mounted in one end of the cross bar 85 and the opposite end is provided with a rigid up-standing guide rod 86 which slidably fits in a vertical hole in the block 82 to prevent the rod 84 turning around. The rod 84 is threaded at its upper end to receive adjustment and locking nuts 87 and 88 and a coil spring 89 is mounted on the lower end of the rod between the cross bar 85 and the block 82 to yieldingly retain the rod 84 at the lower limit of its adjustment. The shoe 58 as thus held can yield vertically, if occasion requires it to do so.

The adjusting nut 87 is provided with very fine longitudinal grooves in its periphery adapted to be engaged by spring fingers 87' which are secured to the block 82. This construction assists in the very fine adjustment of the shoe 78 in relation to the roll 58 and also permits the shoe to be lifted by hand to free any blanks which may be caught between the feed roll and the shoe and without altering the adjustment of the shoe.

To transmit motion from the lever 76 to the cam disk 70 there is provided a transverse shaft 90, (see Fig. 4) which is mounted for rotation at one end in a suitable bearing 91 on the block 82, and at its other end in a suitable bearing 92 formed on a bracket 93 secured on the bar 30 adjacent to the side frame part 41. A depending arm 94 is fixed on the shaft 90 adjacent to the bearing 91, and the upper end 95 of the lever 76 is provided with a transversely extending projection 96 arranged and adapted to engage said arm 94 and swing same to the right, as shown in Figs. 3A and 3B, when the lower end of the lever is 35 swung to the left.

To operatively connect the shaft 90 with the cam disk 70 I provide a depending arm 97 which is mounted on the shaft 90 and is secured thereto to rotate therewith, and a link 98 which is arranged to connect the free end of the arm 97 with the cam disk 70.

The lower end of the link 98 is pivotally connected with the disk 70 by the stop member 74 and to the free end of the arm 97 by a similar 45 connection 99.

The arrangement is such that when the arm 97 is swung back and forth the cam disk is oscillated on its supporting shaft 36. The arm 97 and the link 98 form a toggle-link connection between the shaft 90 and the cam disk 70. In the normal operating position of the parts, as shown in Fig. 3A, the toggle is bent and the cam disk is rotated backwards to hold the cam projection 71 and the roller 72 out of contact with the drum 10, and when the lower or gauging end of the lever 76 is swung to the left the toggle is straightened out and the cam disk to rotate to bring the cam projection 71 and in succession the anti-friction roller 72 into operative contact with the drum 10 and stop the feeder, as has been described.

An upwardly projection handle 100 is provided which is rigid with the arm 97 and by which the toggle can be operated manually either to start the feeder or to stop it. The handle 100 serves as a clamping screw to secure the arm 97 rigidly upon the shaft 90.

For the purpose of re-setting the parts in operation position as soon as the lever 76 is free to swing back to normal operative position, a pull spring 101 is connected at one end to the pivotal connection of the arm 97 and link 98 and at its other end to a part rigid with the machine frame such as a projection 102 rigid with the block 82.

The arrangement is such that as soon as the lever 76 is free to swing back to normal operative position, the spring 101 breaks the toggle and returns the parts to normal feeding positions.

5 The automatic action of disconnecting the feeding mechanism from the source of power and the stopping of the feeding mechanism is practically instantaneous. This action is as follows:

When the forward edge of a double blank contacts with the shoe 78 of the gauge 76 it is guided between the shoe and the feed roll 58 thus lifting the shoe against the action of the spring 89 and pinching the double blank between the shoe and the feed roll and this carries the shoe 78 along with blanks, thus swinging the gauge lever and through the operative connections described causing the rotational movement of the cam 69 which results in the dis-connection of the feeder from the source of power.

20 As the caliper or gauge lever 76 is thus limited in its movement, the rear end of concentric part 79 of the shoe 78 is slightly relieved so that as it is stopped in its swinging movement and has accomplished the disconnecting of the feed roll 58 from the source of power it will no longer pinch the article which caused the stopping. This is for the purpose of preventing any possible further movement of the feed roll from crumpling the blanks between the roll and the shoe as 25 these blanks are often valuable records which it is desired to preserve in the condition they are in when presented to the mechanism. As the cause of the stopping of the mechanism is usually the feeding of two blanks in superposed relation 30 and as these blanks are commonly but a few thousandths of an inch thick, such relieving of the face of the shoe is so light as not to show distinctly in the drawings.

The separating and feeding mechanism shown 40 in the drawings is typical of any means which may be used for separating single blanks from the stack 34 and starting them on their path to be fed into the primary machine.

45 As described, the feeding mechanism is stopped by the entrance between the feed or pull-out roll 58 and the shoe 78 of the gauge lever 76 of any article thicker than the thickness of the contemplated blanks and as the feeder is substantially instantaneously stopped, the fed article, 50 which caused the stopping, will remain between the pull-out roll below and its pressure rolls and the shoe above. But as the shoe 78 is yieldingly held against the feed roll the double blank or whatever effected the stepping of the feeder can 55 be readily pulled out by hand.

The separator, as shown in the drawings, is provided with a supporting board or plate 103 which is pivotally mounted on the side frame parts at 104. The board 103 extends across the 60 machine and is capable of being tilted up and down to cause the blanks to slide down the board for feeding.

65 It is obvious that such a board may be provided for manual feeding of the blanks for which purpose it is tilted down preferably until it is nearly horizontal.

The feeding mechanism when used, is preferably driven through the medium of the friction roll 35 in conjunction with the stop mechanism 70 so that when the stop mechanism operates to stop the roller 58 with its superposed pressure rolls 62, all the power operated separating and feeding mechanism will be stopped.

75 The separating mechanism, as shown, includes

a pair of separator rolls 105 and 106 mounted on shafts 107 and 108 respectively.

As shown in the drawings the separator roll shaft 107 is driven through a train of gears 109 from a counter shaft 110, which in turn is driven from the feed roll shaft 59 through a chain 111, 5 the feed roll shaft 59 and the counter shaft 110 being provided with suitable chain wheels.

It will now be clear that the blank separating mechanism is driven in time with the feed roll 10 58 and that when the feed roll 58 is stopped, the separating mechanism will also be stopped.

As shown the separator shaft 107 is operatively connected to the train of gears through a clutch 112 so arranged that, when necessary, the separator roll can be readily disconnected from the tearing so that if desired it can be easily turned 15 backward.

What I now consider to be a preferable form 20 of clutch for the purpose, is shown in Fig. 9 of my prior Patent No. 1,627,015, issued May 3, 1927, and described in the specification of said patent, beginning with line 75 of page 7 of said patent and to which reference is here made for an 25 understanding thereof without repetition herein. However, the clutch 112 merely exemplifies any desired or approved clutch for the purpose.

As many modifications of the invention will readily suggest themselves to one skilled in the art, I do not limit or confine the invention to the 30 specific details of construction and operation, nor to the specific combinations of devices and mechanisms herein shown and described except within the scope of the appended claims.

I claim:

1. In the combination of a primary machine and a feeder for feeding blanks thereto, the machine having a continuously rotating member, the feeder provided with a friction roller arranged and adapted to be pressed against said member for operating said feeder, the feeder provided with a blank gauge and a cooperating blank feeding roll, the gauge having a part normally spaced from the associated roll to permit the free passage of a blank of contemplated thickness, the gauge being pivotally mounted and adapted to be swung out of normal position by the passage of anything thicker than the contemplated thickness, and operative connection between said gauge and said friction roller for moving the friction roller out of contact with said rotating member of the primary machine when the gauge is so swung.

2. In a blank feeder of the kind described, a feed roll, means for rotating said feed roll comprising a constantly rotating member of a primary machine with which the feeder is associated, the feeder having a friction roll; means for holding the friction roll in operative contact with said rotating member, a blank gauge associated with said feed roll arranged and adapted to permit blanks of contemplated thickness to pass freely through the feeder, but to be moved by the attempted passage of anything thicker than said blanks, and means operatively connecting said blank gauge with said friction roll for moving same out of contact with said rotating member when the gauge is so moved the arrangement being such that the friction roller is automatically reengaged with the constantly rotating member of the primary machine upon the removal of the extra thickness from between the blank gauge and the associated feed roll.

3. The invention as defined in claim 2, the gauge being adjustable from and toward the feed 75

roll for allowing the free passage of blanks of different thicknesses.

4. The invention as defined in claim 2, the gauge being yieldingly held toward the feed roll and being capable of being moved bodily away from the feed roll without disturbing its adjustment.

5. The invention as defined in claim 2, the means for moving the friction roll out of contact with the rotating member comprising a rotatable cam member associated with the friction roll, and operative connection between the cam and the blank gauge for rotating said cam when the gauge is moved.

10 6. The invention as defined in claim 2, the gauge comprising a rocking lever, and the means for moving the friction roll out of contact with the rotating member comprising a rotatable cam member mounted concentric with the friction 20 roll and having a cam projection extending radially beyond the periphery of said friction roll and adapted to be rotated to force the friction roll out of contact with the rotating member, the cam member having an anti-friction roll arranged 25 and adapted to be held in contact with the rotating member when the friction roll is free thereof, and operative connection between said rocking lever and said cam member for moving the cam into operative position when the lever is 30 rocked.

7. The invention as defined in claim 2, the means for moving the friction roll out of contact with the rotating member including a toggle arranged to be normally in bent condition and to 35 be straightened to effect the disconnecting movement of the friction roll, and means for manually operating the toggle.

8. The invention as defined in claim 2, the means for moving the friction roll out of contact with the rotating member including a rotatable cam member mounted concentric with said friction roll and having a cam projection extending 5 radially beyond the periphery of the friction roll, and a toggle member interposed between the cam member and the blank gauge and arranged to be normally bent, and to be straightened by the gauge when same is moved to rotate the cam 10 member, and means normally yieldingly retaining the toggle in bent condition.

9. The invention as defined in claim 2, the operative connection between the blank gauge and the friction roll, including a rock shaft, a rigid 15 projection on the rock shaft adapted to be engaged by the gauge and to be moved to rock the shaft upon the movement of the gauge due to the attempted passage through the feeder of any article thicker than the contemplated blanks, a 20 second arm rigid with the rock shaft, a rotatable cam member mounted concentric with the friction roll, a cam projection on the cam member extending radially beyond the periphery of the friction roll, a link connecting the free end of 25 the said second arm with the cam member and adapted to rotate the cam to force the friction roll away from said rotating member when the gauge is moved, a stop for limiting the rotational movement of the cam member, and an anti-friction roller carried by the cam member and adapted 30 to contact with the rotating member when the cam member is held by said stop.

WM. WARD DAVIDSON. 35
